EZEKIEL TRACY, OF KANSAS CITY, MISSOURI.

Letters Patent No. 71,822, dated December 3, 1867.

IMPROVEMENT IN BURGLAR-ALARM DOOR-LOCKS.

The Schedule referred to in these Letters Patent and making part of the same.

TO ALL WHOM IT MAY CONCERN:

Be it known that I, EZEKIEL TRACY, of Kansas City, in the county of Jackson, and State of Missouri, have invented a new and improved Combination of an Alarm and Lock; and I do hereby declare that the following is a full, clear, and exact description thereof, which will enable others skilled in the art to make and use the same, reference being had to the accompanying drawings, forming part of this specification.

The present invention consists in so combining an alarm with a lock, and arranging it in connection therewith, that in unlocking the lock an alarm will be set free and sounded, and thus the approach and entrance of burglars, or other parties, indicated to the occupants of the premises or room where the lock is applied. In the accompanying plate of drawing my improved combination of an alarm and lock is illustrated—

Figure 1 being a view of the interior of the lock, showing the locking-mechanism and the connection between it and an alarm.

Figure 2, a view of the key to the lock, shown in fig. 1.

Similar letters of reference indicate corresponding parts.

A, in the drawings, represents a box or case, in which the locking-mechanism B is arranged, and an alarm-bell, C, that by a hammer or striker, D, is sounded, when the coiled spring E is allowed to act upon such hammer, to throw it against the bell. F, the bolt of the locking-mechanism, which, through the key G, shown in fig. 2, is thrown out or drawn in in the operation of the key-bit upon the tumbler-plate H, and the notch I of the tail or inner end of the bolt. K, a bar arranged across the bolt F, so set over the same, that on the turning out or drawing in of the bolt, the bolt, through the cut-out portion of its edge M, will be moved across the plane of movement of the bolt, on which movement it will be guided by the guides N, suitably located therefor, on the lock-case A. O, a spring, for forcing the bar back to its usual position, after being moved by the bolt F, as just above stated. This bar K, by its lower end, when in the position shown in the drawings, sets into one of two notches, P P; a bolt, Q, that is arranged within the lock, to slide in and out thereof, running through the plates Q of the same. This bolt Q passes through the portion of the case A wherein the alarm is arranged, and at or near its end therein has a pin, S, by means of which the stem T, to the bell-hammer, is held stationary when the bolt is out or the lock is locked, as is shown in the drawings.

In the unlocking of the lock, as the bolt is drawn in, to unlock the lock, the bar K is raised, and thus the bell-hammer stem set free for sounding the bell, by following the bolt Q to move out through the action of its spring U, and thus to remove the pin thereof from holding the said hammer-stem.

I claim as new, and desire to secure by Letters Patent—

The combination of the lever-bar B and supplementary bolt Q, when arranged between the mechanism of lock and a suitable alarm, for operating substantially as and for the purpose described.

EZEKIEL TRACY.
